UNITED STATES PATENT OFFICE.

WILLIAM C. YATES, OF SCHENECTADY, NEW YORK, ASSIGNOR TO GENERAL ELECTRIC COMPANY, A CORPORATION OF NEW YORK.

MOTOR-CONTROLLING RHEOSTAT.

No. 910,343.

Specification of Letters Patent. Patented Jan. 19, 1909.

Application filed July 8, 1907. Serial No. 881,997.

To all whom it may concern:

Be it known that I, WILLIAM C. YATES, a citizen of the United States, residing at Schenectady, county of Schenectady, State of New York, have invented certain new and useful Improvements in Motor-Controlling Rheostats, of which the following is a specification.

This invention relates to devices for controlling electric motor circuits and has for its object the provision of a device of this character in which the motor speed may be regulated and a general control of the motor effected in a reliable, simple and efficient manner.

My invention relates more specifically to devices for starting electric motors and varying the speed thereof after the running conditions have been established.

In carrying out my invention I provide in connection with the starting and speed regulating resistances, a controlling arm for each mounted independently and spring-pressed to return to its initial position. The starting arm is spring-pressed to the starting position while the field arm is spring-pressed to the full field position. The two arms are so arranged that when the starting arm is moved to running position a pair of gears, one on the field controlling arm and the other on the operating handle of the starting arm, are caused to mesh so that by turning the operating handle the field resistance may be varied. I also provide means whereby as the starting arm moves toward running position, it relieves the field arm of its spring tension so that when running conditions are established, the field arm will remain in any position in which it is left. The starting arm is retained in the running position in the usual manner by a no-voltage magnet and upon failure of voltage both arms return to their initial positions.

In the accompanying drawing in which I have shown one embodiment of my invention, Figure 1 is a plan view of my device showing the circuit connections; Fig. 2 is a similar view on a smaller scale with the parts in running position, the field arm being turned so as to throw a resistance into the field circuit and speed up the motor; and Fig. 3 is a side elevation of the working parts of my device.

Referring to the drawing, 10 is an insulating base of slate or soap-stone having mounted thereon a series of contacts 11 arranged in the arc of a circle and forming the terminals of starting resistance 12. A contact arm 13 is pivoted at 14 so that the contactor 15 at its free end engages the studs 11 to vary the starting resistance. The arm is biased or spring-pressed to starting position against the stop 16 by means of a spring 17. An operating handle 18 is mounted to turn in the arm 13 and has secured to it a gear 19. The arm 13 is preferably bent as shown so that the handle will have a bearing in the bent portion 20 as well as in the upper portion and the gear will be between the two bearings. A no-voltage magnet 21 is arranged to retain the arm in the running position in the usual way. A series of contact studs 22 arranged in the arc of a circle form the terminals of field resistance 23. A controlling arm 24 pivoted at 25 is mounted to rotate so that its free end engages the studs 22 to vary the field resistance. This arm is biased to its initial position as shown in Fig. 1 by means of the spring 26, one end of which bears against the pin 27 in the base and the other end against the pin 28 on the hub gear 29. This hub gear is secured to and rotates with the arm 24. The end of the spring 26, which engages the pin 28, has an extension 30 beyond the pin lying in the path of the arm 13 so that as the arm 13 is moved towards running position it engages the spring and forcing it away from the pin 28 relieves the tension on the arm 24. When the arm 13 reaches running position, in engagement with the no-voltage magnet 21 the gear 19 will mesh with the gear 29 so that by turning the handle 18 the arm 24 may be turned through the gear connections.

The arrangement of circuits and the mode of operation are as follows: When the arm 13 is turned to the right by means of the handle 18 to start the motor, current passes from the line 31 through the arm 13, starting resistance 12, conductor 32, armature A of the motor and back to line 33. At the same time the field circuit passes from line 31 through arm 13, conductor 34, arm 24, thence through field F to line 33. When the arm reaches running position and is held there by the no-voltage magnet, the spring

- 5 tension on the arm 24 is relieved and at the same time gears 18 and 29 are brought into mesh. By then turning the handle 18 the field control arm 24 may be turned as shown in Fig. 2 so as to speed up the motor. Upon failure of voltage arm 13 will return to starting position and the spring tension being once more returned to the arm 24, the latter will also return to its initial position.
- 10 It will thus be seen that I have provided a very simple device for starting the motor and controlling the speed thereof, the arrangement being such that the motor is always started with a maximum field strength. It 15 will be understood, of course, that various modifications of my device will suggest themselves to those skilled in the art without departing from the spirit of my invention, the scope of which is set forth in the annexed 20 claims.
- What I claim as new, and desire to secure by Letters Patent of the United States, is,—
1. A controlling device for electric motors 25 comprising a pair of resistances, each provided with an independent controlling arm, and means in connection with one of said arms and inoperative until the arm stops at a predetermined position for moving the 30 second arm to vary its resistance.
2. A controlling device for electric motors comprising a starting and a field resistance provided with independently movable controlling arms, and means for rendering the 35 field arm operative only when the starting arm is in running position.
3. A controlling device for electric motors comprising a pair of resistances, each provided with an independent controlling arm, 40 and means mounted upon one of said arms and inoperative until the arm stops at a predetermined position for moving the second arm to vary its resistance.
4. A controlling device for electric motors 45 comprising a starting resistance and a field resistance, each provided with an independent controlling arm, and means movable with the starting arm and inoperative until the arm stops at its running position, for 50 moving the field arm to vary its resistance.
5. A controlling device for electric motors comprising a pair of resistances, each provided with an independent controlling arm biased, to an initial position, and means 55 whereby the bias is removed from one of said arms as the other is moved from its initial position.
6. A controlling device for electric motors comprising a starting resistance and a field 60 resistance, each provided with a spring-returned controlling arm, and means whereby the spring tension is removed from the field arm as the starting arm is moved towards running position.
7. A controlling device for electric motors 65 comprising a spring-returned starting mechanism and a no-voltage magnet therefor, a field controlling arm, and a device movable with the starting mechanism and inoperative until the running position is reached for 70 moving the field arm.
8. A controlling device for electric motors comprising a spring-returned starting mechanism and a no-voltage magnet therefor, a spring-returned field controlling arm, means 75 for removing the spring tension from the field arm when the starting mechanism reaches running position, and a device movable with the starting mechanism and inoperative until the running position is 80 reached for moving the field arm.
9. A controlling device for electric motors comprising a pair of resistances, each provided with an independent controlling arm, and gearing upon said arms arranged to 85 mesh so as to operate one arm from the other when the latter reaches a predetermined position.
10. A controlling device for electric motors comprising a pair of resistances, 90 each provided with an independent controlling arm, an operating handle for one of said arms, and a gear connection between said handle and the other arm for moving the latter arm when the operating arm 95 reaches a predetermined position.
11. A controlling device for electric motors comprising a resistance, a controlling arm therefor having an operating handle movable on said arm, a gear driven by said 100 handle, a second resistance controlling arm provided with a driving gear, said gears being arranged to mesh so as to drive the second arm from the operating handle when the first arm reaches a predetermined 105 position.
12. A controlling device for electric motors comprising a spring-returned starting mechanism having an operating handle movable independently thereof, a field controlling arm and gearing arranged to mesh 110 between said handle and said field arm when the starting mechanism is in running position.
13. A controlling device for electric 115 motors comprising a starting resistance, a controlling arm therefor having an operating handle movable independently thereof, a gear driven by said handle, a field resistance and a controlling arm therefor having a 120 driving gear mounted thereon, said gears being arranged to mesh when the starting arm reaches running position.
14. A controlling device for electric 125 motors comprising a starting resistance, a spring-returned controlling arm therefor, a gear and means for driving the same mounted upon said handle, a field resist-

ance, a spring-returned controlling arm therefor, a drive gear for said arm, said gears being arranged to mesh when the starting arm reaches running position, and 5 means for removing the spring tension from the field arm when the starting arm reaches running position.

In witness whereof, I have hereunto set my hand this first day of July, 1907.

WILLIAM C. YATES.
